UNITED STATES PATENT OFFICE.

CHARLES GALE ADAMS, OF JOLIET, ILLINOIS.

HOT-WATER BOILER.

Application filed October 2, 1922. Serial No. 591,714.

To all whom it may concern:

Be it known that I, CHARLES GALE ADAMS, a citizen of the United States, and a resident of the city of Joliet, in the county of 5 Will and State of Illinois, have invented certain new and useful Improvements in a Hot-Water Boiler; and I do hereby declare that the following is a full, clear, and exact description of the same, reference being had to the accompanying drawings, and to the numerals of reference marked thereon, which form a part of this specification.

This invention relates to a new and useful water heating boiler built up of welded 15 boiler plate in such a way as to reduce the number of parts and the length and number of joints to a minimum as well as producing a reliable and economical heating boiler.

Heretofore hot water boilers have been 20 made of cast iron sections, either horizontally or vertically jointed and the assembly thereof has been much more expensive than the factory assembly costs of a welded seam boiler such as disclosed herein. Moreover, 25 the present day cast iron boilers are extremely difficult to clean because of the many joints and tortuous passages therein.

It is an object of this invention to provide a steel boiler suitable for residential use that 30 will be as simple, compact and easily cleaned as possible.

It is a further object of this invention to construct a practically all-steel boiler with the fewest possible seams and therefore a 35 boiler that may be practically manufactured to sell at a reasonable price especially in comparison with the cost of cast iron heating plants.

It is an important object of this invention 40 to provide a compact and light boiler that may be sold and installed as a unit rather than a number of sections that require highly skilled labor for assembling in place.

It is a further important object of this 45 invention to provide a completely water-jacketed firebox, and to pass the flue gases therefrom twice through the hottest water at the top of the furnace, thus utilizing as much as possible of the heat evolved by the 50 fuel burned.

It is a very important object of this invention to so design a heating boiler that it can be built up of welded plates with only the doors and door frames made of cast 55 metal.

Other and further important objects of

this invention will be apparent from the disclosures of the drawings and specification.

The invention (in a preferred form) is 60 illustrated in the drawings and hereinafter more fully described.

On the drawings:

Figure 1 is a front elevation of a boiler embodying the preferred form of this in- 65 vention.

Figure 2 is a side elevation thereof.

Figure 3 is a top plan view thereof.

Figure 4 is a section on the line 4—4 of 70 Figure 3.

Figure 5 is a section on the line 5—5 of Figure 4.

Figure 6 is a section on the line 6—6 of Figure 4.

Figure 7 is a section on the line 7—7 of 75 Figure 4.

As shown on the drawings:

The reference numeral 1 denotes a base and ash pit, supporting grate bars 2, as well as the boiler proper. This ash pit is of 80 course provided with a door 3 to permit removal of the ashes. The boiler proper comprises a unitary outer shell 4 fitted with a charging door frame 5 and door 6 at the proper height with reference to the grate. 85 Inside the shell 4 and coaxial therewith is an inner shell or firebox 7 having an annular ring 8 welded to its bottom and to the bottom of the outer shell to completely close the same. Fillers 9 are also of course inserted between the inner and outer shells at the charging door opening.

A crown sheet 10 slanting upwardly from the top of the charging door frame is apertured for a plurality of flues 11, and is 90 welded to the top of the inner shell 7, thus forming a completely water-jacketed firebox. The flues 11 lead upwardly to a tube sheet 12 located at the front and top of the outer shell, which, in connection with a 100 cover or frame 12^a secured to the outer shell, forms a chamber 13 leading to a second set of horizontal flues 14 leading through to a smoke box 15 formed at the back of the boiler, where smoke stack connection 16 is 105 located. The front smoke box or chamber 13 is provided with cleaning doors 17 and 18 to permit the use of flue brushes through the various boiler flues.

The boiler is completed by the addition 110 of a cold water supply connection 19 near the bottom of the outer shell and a hot wa-

ter outlet 20 near the top of the shell, both preferably on one side of the boiler.

The operation of this boiler needs little explanation, as it will be apparent that the 5 gases from the burning fuel on the grate bars 2 will pass upwardly through the nearly vertical flues 11 into the front smoke box or chamber 13 and thence through the horizontal flues 14 into the rear smoke box 15 and into the stack or chimney through the 10 connection 16. The water in the boiler will have a natural circulation from the bottom upwardly around the flues 11 and 14.

The boiler of this invention may be conveniently adapted for use as a garbage burner and may also be used as a steam boiler by embodying slight modifications.

It will be apparent that by the provision of a structure embodying this invention it 20 is possible to produce boilers and the like which are entirely free from rivets, which are strong in construction, and which may be economically manufactured.

I am aware that numerous details of construction may be varied through a wide 25 range without departing from the principles of this invention, and I therefore do not purpose limiting the patent granted otherwise than necessitated by the prior 30 art.

I claim as my invention:

1. In a water heating boiler, a cylindrical outer steel shell, an inner steel shell coaxial

therewith forming a water jacketed fire box, a crown sheet over said inner shell, a smoke 35 box at the front and top of the outer shell, a plurality of substantially vertical flues leading from said crown sheet into the upper portion of said smoke box, a second smoke box and chimney connection near the 40 top and rear of said outer shell, and horizontal flues leading from the lower portion of said first mentioned smoke box to said second smoke box.

2. A device of the class described, comprising a welded outer jacket, a welded inner shell forming in connection with grate bars a fire box, means connecting said jacket and said shell to form a water jacket around said shell, a welded crown sheet on said jacket, a crown sheet secured thereabove forming a compartment at the front and top of said jacket, a plurality of substantially vertical flues leading from said fire box to the upper portion of said compartment, and horizontal flues leading from the lower portion of said compartment to an outlet welded to the rear of said jacket.

In testimony whereof I have hereunto subscribed my name in the presence of two 60 subscribing witnesses.

CHARLES GALE ADAMS.
